UNITED STATES PATENT OFFICE.

FREDERIC OAKFORD, OF PHILADELPHIA, PENNSYLVANIA, ASSIGNOR OF ONE-HALF
TO ARTHUR W. JONES, OF GERMANTOWN, PHILADELPHIA, PENNSYLVANIA.

HUMIDOR.

1,423,356.

Specification of Letters Patent.

Patented July 18, 1922.

Application filed November 5, 1920. Serial No. 421,853.

To all whom it may concern:

Be it known that I, FREDERIC OAKFORD, a citizen of the United States, residing in Philadelphia, Pennsylvania, have invented 5
5 Humidors, of which the following is a specification.

One object of this invention is to provide a relatively simple, inexpensive device particularly designed for use with or attachment 10 to a metallic cigar box whereby a limited amount of moisture may be supplied to the contents of such box and in which the construction and arrangement of parts is such as to permit of the convenient removal 15 and replenishment of the member from which the moisture is supplied.

These objects and other advantageous ends I attain as hereinafter set forth, reference being had to the accompanying drawings, 20 in which,

Fig. 1 is a perspective view of a cigar box showing my invention as applied thereto;

Figs. 2 and 3 are respectively an end and a rear side elevation of the box shown in 25 Fig. 1;

Fig. 4 is an elevation of the inner side of the removable moisture supplying member; and

Fig. 5 is a transverse section on an enlarged scale, taken on the line 5—5, Fig. 4.

In the above drawings 1 and 4 represent respectively the front and rear sides of a cigar box having ends 2 and 3, a bottom 5 and a cover 6 and while I have illustrated 35 this box as made of sheet metal and while my invention is particularly applicable to a metal box, it will be understood that it may without material change be applied to wooden and other containers.

40 In accordance with my invention the rear side 4 has a number of perforations 7 and its outer face is provided with a guideway and other retaining means for a thin, moisture containing member 8. Such guideway 45 in the present instance is provided by a series of prongs or tongues 9 pressed out in two sets from the upper and lower portions of said side 4, in addition to which a similar tongue 10 is pressed out at one end of said

side to limit the movement of said member 8.

This latter is held in its guideway by friction or by any suitable device and in the present instance consists of a body of sheet metal folded in two parallel sections of 55 which one is imperforate and the other has a number of relatively large openings or perforations 11, although obviously the size, arrangement and number of these is immaterial. Confined between the two thicknesses 60 of the sheet metal constituting the main portion of the member 8 is a sheet 12 of a porous material such as blotting paper which will absorb and retain water. The member 8 in the present instance is not only flat and 65 relatively thin, even after the introduction of the blotting paper, but is parallel sided and of such width as to slidably fit the guideway provided by the tongues 9.

In utilizing this device, the blotting paper of the member 8 is saturated with water, after which said member is slid into place in the guides 9, with its perforated face immediately adjacent the perforated rear side 4 of the box. In this position it is 75 obvious that moisture is supplied through the perforations or openings 11 of the holder and through the perforations 7 of the box to the cigars or cigarettes which may be contained within the latter and if desired or 80 found advisable, the front side of said box may be provided with openings 14 to facilitate the passage of the water vapor from the blotting paper into and through the cigars, cigarettes, etc., within the box. 85

By this means said cigars, etc., are prevented from drying out or molding and when necessary the member 8 may be removed and the blotting paper supplied with additional water. This device is particularly adapted for application to filled cigar boxes constituting original packages, although by no means limited to such use, and it is to be particularly noted that its manufacture and application to metal or other 90 cigar boxes may be accomplished with but little increase in the cost thereof.

While I have shown my invention as ap-

plied to a box of rectangular section, obviously the form of said box is immaterial.

I claim:

The combination of a container having a 5 perforated face and struck up tongues constituting a guideway on said face; a relatively thin holder slidably mounted in the guideway provided by said tongues and con-

sisting of two spaced thicknesses of sheet metal; with a sheet of water absorbent material mounted within the holder, the outer face of the latter being imperforate and the face adjacent the perforated side of the container having openings therein. 10

FREDERIC OAKFORD.
